SPECIFICATION forming part of Design No. 15,574, dated November 25, 1884.

Application filed October 1, 1884. Term of patent 3½ years.

To all whom it may concern:

Be it known that I, MARY KAVANAGH, of the city, county, and State of New York, have invented and produced a new and original 5 Design for a Pattern of a Miss's Cloak, (numbered 9,493;) and I do hereby declare that the engraved prints accompanying this specification convey to any one accustomed to using paper patterns a clear understanding of how 10 a garment made up by the pattern will appear.

The design shows loose-fitting double-breasted fronts exhibiting a fastening all the way
